Patented Dec. 10, 1963

197,102

FIREPLACE GRATE FOR BURNING ROLLED NEWSPAPERS OR THE LIKE

Edward R. Pryor, Masons Island, Mystic,
New London County, Conn.

Filed Sept. 13, 1962, Ser. No. 71,678

Term of patent 14 years

(Cl. D81—18)

FIG. 1

FIG. 2

FIG. 4

FIG. 1 is a perspective view of a fireplace grate for burning rolled newspapers or the like, showing my new design;

FIG. 2 is a top plan view of the same;

FIG. 3 is a front elevation; and

FIG. 4 is a right side view.

I claim:

The ornamental design for a fireplace grate for burning rolled newspapers or the like, as shown.
